HYDRAULIC PUMP OR MOTOR

Elick K. Benedek, Bucyrus, Ohio

Application January 25, 1935, Serial No. 3,455

12 Claims. (CL 103—161)

This invention relates to pumps and motors of the radial piston, variable displacement type and particularly to pumps and motors of this character adapted for providing high hydrostatic pressure for use in connection with heavy hydraulic power driven machines, transmissions, presses and the like, one of the purposes being to create a compact and efficient unit for hydraulically transmitting as much as 500 horsepower and above.

Prior pumps of this general type comprise the usual driving and driven members with the radial pistons, rigidly or flexibly engaging one of the members and reciprocating in pump cylinders in the other for providing the necessary hydrostatic head. However, in such prior structures, the pistons and their mountings not only perform their primary function as hydraulic members but provide the sole mechanical coupling means for transmitting driving torque from the driving member to the driven member. Necessarily, for providing the desired hydraulic pressure, the piston assemblages and their mountings are subjected to the very high radial compressive forces. Concurrently, in order to drive the driven member through the medium of the piston assemblages, heavy tangentially or peripherally directed forces necessary for driving torque are transmitted to the various parts of the piston and cylinder assemblages, subjecting the parts to severe bending stresses and moments.

These stresses result not only in extremely high frictional resistances but also undue wear, especially between the pistons and the walls of their respective cylinder bores and between the piston crossheads and their respective guides. Since a close fit therebetween is necessary, the wear thus occasioned results in short useful life of the pump. Obviously, these bending stresses are augmented disproportionately when simultaneous with the compressive radial reactances to which the pistons are subjected in providing the hydrostatic pressure. This conjoint effect, is such as to render the prior pumps practically useless for the higher pressures sought to be obtained by the present pump due to the fact that the pistons of the former seize in their respective cylinders as also do the crossheads in their guides.

In such pumps, the useful life inherent in the materials used is seldom reached, the failure being caused not by excessive slip and heat but by the fact that the pistons and their crossheads are rocked and forced out of coaxial position with respect to their cylinder and crosshead guide

walls and seize therein so as to render further operation of the pump impossible.

Since, in such pumps, whether of the T-shaped piston, integral plunger and crosshead type, the flexible crosshead type, or hollow plunger push pin type, the sole means of torque transmission between the driving and driven members are primarily the pistons and their cooperating cylinder walls, each piston must transmit from the driving member to its crosshead and thence to the driven member a force couple substantially equal to a part of the entire torque of the driving member inversely proportional to the number of pistons employed.

The flexible crosshead type, due to the rocking of the push pins in the hollow plungers, is inadequate for proper torque transmission, the plungers themselves being small and the push pins necessarily smaller. It is clear therefore why the flexible piston type of radial pumps has never reached safely a capacity of more than 100 horsepower.

The T-head piston type lends itself to higher capacities due to the more rigid structure of the pistons and their integral crossheads which make possible the transmission of a heavier torque. This type has been found useful up to 200 horsepower.

Such pumps may well be designated collectively as "coupling pumps" the expression being used in its literal sense, inasmuch as the sole mechanical coupling for transmitting torque from the driving to the driven member is the pump mechanism, including the pistons, cylinders, and crosshead assemblages. These practical and structural limitations inherent in prior pumps of this character, however, render them useless for the higher pressures now required in many machines.

With this brief review of the structures of prior pumps or motors and the difficulties encountered in connection therewith in mind, the advantages and principles embodied in the present structure will be clear.

One of the principal objects of the present invention is to provide a pump or motor of the radial piston type in which the torque transmitting and coupling functions of the radial pistons are entirely eliminated and in which the driving torque between the primary and secondary rotors is transmitted by an efficient mechanical coupling entirely independent of the piston assemblages themselves insofar as concerns torque transmission.

Another object is to provide an improved T-

55

shaped piston structure such that no forces, other than the direct radial forces necessary for the hydraulic action, will be transmitted from the rotors to the piston assemblages.

5 A correlative object is to provide a T-shaped piston structure in which the piston, crosshead and cooperating reactance parts are so arranged that localized reactionary forces of a nature tending to develop force and reactance couples and 10 bending moments among the various parts are eliminated and the pistons are subjected only to true radial reactance forces so that not only is the power delivered to the piston for creating hydrostatic head utilized fully but also none of it 15 is wasted or misapplied so as to create unnecessary stresses and frictional resistance between the pistons and their cooperating mountings and cylinder walls.

20 A more general object is to provide a pump of this character in which any forces tending to tilt the rotor due to the torque applied to it from the impeller shaft is overcome and resisted without being transferred to the pistons or to the secondary rotor and in which all bearing surfaces 25 and points of application of pressures between the component parts are symmetrical with respect to the axes of the piston so that an efficient balance is provided throughout the mechanism.

30 Another object is to provide a stroke controlling mechanism which rotatably supports a secondary rotor in a simplified manner.

35 - A more specific object is the provision of a simplified means for mounting the pistons in the piston actuating mechanism.

40 A marked advantage of my invention resides in the more efficient operation of the apparatus resulting from the cooperative relations among the new coupling means, the new piston actuating means, and the piston assemblages themselves.

45 Other important features include individual reactance segments for each piston, the manner in which they are mounted in position relative to the secondary rotor, the manner of assembling and disassembling the driving coupling means between the rotors and their driving connection to the primary rotor so as to eliminate both mechanical unbalance and hydrostatic deflection of the 50 rotating parts.

55 Other objects and advantages will become apparent from the following specification wherein reference is made to the drawings in which

Fig. 1 is a longitudinal side elevation of a pump embodying the principles of the present invention;

Fig. 2 is an end elevation of the pump illustrated in Fig. 1 taken from the valve end thereof;

Fig. 3 is an enlarged horizontal sectional view of the pump taken on a plane indicated by the line 3-3 of Fig. 2;

Fig. 4 is a transverse sectional view of the pump taken on a plane indicated by the line 4-4 in Fig. 1;

Fig. 5 is a perspective view of one of the segmental reaction blocks;

Fig. 6 is a perspective view of the piston connecting spring;

Fig. 7 is a perspective view of one of the component elements of the driving coupling; and

70 Fig. 8 is a fragmentary transverse sectional view of the pump driving coupling taken on the line 8-8 of Fig. 3, a portion thereof being taken on the line 8'-8' of Fig. 3 for clearness in illustration.

Referring to the drawings, which illustrate a preferred embodiment of my invention, the pump or motor mechanism is enclosed in a housing comprising a central cylindrical body portion 1, closed at the ends by end portions 2 and 3 respectively. The end portion 3 is provided with an enlarged heavy hub 4 adapted to receive the valve pintle for the rotors, later to be described. The end portion 2 is provided with an outwardly protruding bell-shaped portion 5 to accommodate the balanced rotor of the mechanism. Part way out radially from the axis of the hub 4, the end portion 3 is provided with an internal annular recess 7, the end portion 2 being provided with a coaxial internal annular recess 6 of equal diameter. These recesses receive the outer races 8 of anti-friction bearings 10-10, the radial end walls of the recesses forming abutments for resisting axial outward displacement of the bearing races 8. Complementary inner bearing races 9 are mounted on coupling members 11, later to be described, and through the medium of the coupling members, rotatably support the driving rotor 12. The anti-friction bearings 10 are of substantially the same size for both races and are of the heavy duty type operating in circumferential channels in the races so as to resist axial displacement of the races and consequently operate as thrust bearings as well as resisting radial pressures.

30 The primary rotor of the mechanism comprises a piston cylinder barrel 12 having at one end an annular reduced diameter hub portion 13 on which is telescopically received a coupling member 11 which, in turn, engages the inner bearing race 9 at that end so that the reaction forces transmitted to the bearings 10 from the end portion 3 of the casing are directly transmitted thereby to the coupling member 11 and barrel 12. A corresponding coupling member 11 is provided at 40 the opposite end of the barrel 12 and cooperates in the same manner with the bearing race 9 at that end. The coupling members 11 are secured against axial displacement toward the longitudinal midportion of the barrel 12 by radial shoulders 14 and 15 on the barrel 12, at the inner limits of the hub portions. Relative axial separation of the members 11 is resisted by radial walls of the recesses 6 and 7 of the housing, through the medium of the bearing races 8 and 9, and bearings 10. Thus the coupling members are so fixed in axial relation to the barrel 12 as to form therewith a substantially unitary structure.

45 As better illustrated in Fig. 8, each of the coupling members 11 has an integral radial flange 11', later to be described. The proper angular relation of the coupling members 11 is maintained by appropriate feather keys 56 between the coupling members 11 and the barrel 12. In addition an accurate snug fit is provided between the annular hub portions of the coupling members 11 and corresponding ends of the barrel. In case of large units the hub portions of the barrel 12 may be tapered and the coupling members 11 correspondingly internally tapered and fitted firmly thereon to prevent developing of any looseness therebetween.

55 The barrel 12 is provided with an axial bore extending entirely therethrough, the end of the axial bore adjacent the driving end of the barrel being tapered, as indicated at 18, to receive the complementary tapered end 23 of the main impeller shaft 24, the shaft being drawn tightly into the tapered bore of the barrel as by a suitable 70 60 65 75 80 85 90 95 98 99 100

lock nut 32 cooperating with the threaded portion 24' of the shaft. A key 26 is provided to secure the barrel and shaft against relative rotation. The impeller shaft 24 terminates inwardly 5 of the rotor at about the inner plane of the coupling elements 11. From slightly beyond this point toward the opposite end of the barrel extends a valve portion 19 of the axial bore of the barrel. Rigidly mounted in the hub 4 at the opposite end of the casing from the impeller shaft 10 is the enlarged shank of a pintle 27, the pintle extending from the hub 4 into the axial bore of the barrel into closely spaced endwise relation to the end portion of the impeller shaft. The pintle 15 27 is provided with a valve portion 26 complementary to the valve portion 19 of the barrel and preferably fitting the wall of the portion 19 with a slight taper fit in such manner that any axially exerted pressure component due to the taper may 20 be readily taken up by the anti-friction bearings 10. The valve portions 26 of the pintle and 19 of the barrel bore are fitted with a highly polished hydraulic fit so as to permit rotation of the barrel thereabout without undue leakage of oil therebetween. The end portion 13 of the barrel adjacent 25 the hub 4 is provided with a counterbore 13' of sufficient length and diameter to provide radial clearance between the enlarged end of the pintle and the barrel and to provide axial clearance, as indicated at 20, between the shoulder of the pintle 27 and the radial shoulder of the barrel at the end of the valve portion. By this arrangement, the heavy rigid portion of the pintle may be 30 brought as near as possible to the valve portion of the pintle so as to provide greater rigidity to better withstand the hydrostatic load imposed on the valve portion 26.

As previously stated, the end of the hub portion 13 of the barrel in cooperation with the hub portion 40 of the coupling member 11 at that end of the barrel rigidly mounts the rotary barrel for torque transmission. The corresponding mounting at the other end of the barrel 12 likewise functions so that tipping of the barrel relative to the axis of the pintle, which usually results from torque transmission from an impeller acting on one end 45 of the barrel, is fully eliminated.

The valve portion 26 of the pintle is provided with the conventional reversible ports, indicated 50 at 28 and 29, the ports being separated by the usual bridge portions 26' and 26'' as better illustrated in Fig. 4, which bridge portions terminate circumferentially into appropriate radial pockets 52, 52' and 53, 53' respectively, thus fixedly defining the circumferential length of each bridge portion and providing accurate and positive timing between the piston cylinder ports of the cylinder barrel or rotor 12 and the ports of the pintle. The ports 28 and 29 communicate respectively with ports 30 and 31 through the conventional axially bored passages, as better illustrated 60 in Fig. 4, and through the ports 30 and 31 finally communicate with the main pump heads 54 and 65 respectively, shown in Figs. 1 and 2.

The piston cylinders 17 of the rotor 12 are arranged in a radial plane so that their axes lie midway between the bearings 10 of the rotor 12. Each of the coupling members 11 is provided with a circular radial flange 11', as previously mentioned, these flanges extending radially parallel to the pistons and being positively secured to respective end portions of the rotor 12 through the medium of their axially extending hub portions. 70 In each radial flange portion 11' are a plurality

of circumferentially spaced radial slots 48, opening radially outwardly. Reciprocably mounted within each slot is a coupling block 40, each coupling block being provided with a radial prismatic portion 40' which is received between the side walls of the slot 48 as a guideway and is reciprocable radially therebetween. From the face adjacent the barrel 12 of each prismatic portion of each coupling block 40, protrudes a crosswise portion 40'' which is received in a tangential slot 10 38''' formed in a coupling plate complementary to the coupling member 11, as better illustrated in Fig. 3, each coupling plate 38 forming a part not only of the coupling structure but also of the piston actuating assembly. Each plate 38 is provided with a piston actuating shoulder positioned to underlie the piston thrust plate, later to be described, in contact therewith so as to lift the thrust plate for moving the piston associated therewith on the suction stroke. These complementary contact surfaces, indicated at 38'', of each plate 38 and associated thrust plate are preferably tangentially extending planes, so that the thrust plate is guided by the coupling plate 38 during the successive cycles of the pump and prevented from rocking or tilting. The coupling plates 38 extend generally radially and near their outer margins are provided with arcuate shoulders 39' which are engaged with and rigidly secured to the secondary rotor 43. The cooperating shoulders of the coupling plates 38 and the secondary rotor will thus transmit any radial thrust imposed on the plates directly to the secondary rotor 43. Corresponding coupling plates are provided at opposite ends of the secondary 35 rotor and these coupling plates are rigidly secured against each other and against the end faces of the rotor 43 by suitable cross members 51, illustrated in Figs. 4 and 8, which clamp them in firm engagement with the rotor 43 for movement directly therewith.

As above mentioned, each coupling plate 38 is provided with a tangential slot 38''' preferably of the taper or dovetail type. The member 40'' is complementarily tapered so as to retain the coupling member 40 and plate 38 fixed axially of the rotor with respect to the remainder of the assembly and to each other. Thus during the driving operation, each of the blocks 40 can shift radially to compensate for the radial component of the eccentricity of the rotors and, through the medium of the slot 38''' and cross member 40'', can shift slightly circumferentially relative to the associated plate 38 and thereby compensate for the circumferential component of the eccentricity. It should be noted that each coupling block 40 and its mountings are positioned circumferentially of the rotors so as to lie in a plane defined by the axes of the pintle and of the respective pistons. Consequently all torque forces can be more efficiently applied close to and symmetrically with respect to the pistons.

It should be noted that the coupling blocks 65 40 reciprocate in the slots 48 a distance equivalent to the maximum pump stroke and the torque transmission from the primary rotor to the secondary rotor through the coupling occurs substantially at the radial distance of the tangential lug 40'' from the axis of the pintle. Due to this long torque arm, which is greater than the length of the piston and even greater than the radial distance of thrust plates or crossheads which in conventional pumps carry the torque, 70 75

the torque is applied to the secondary rotor near its outer limit and the secondary rotor mechanism therefore is subjected to lower bending stresses. Since most of the driving torque is transmitted by the blocks 40 they are preferably of forged alloy steel, heat treated, hardened and ground so that they will stand not only great internal stress but will have wear resisting and smooth sliding coupling surfaces. Each of the radial cylinders in the rotor 12 is arranged in the plane of the longitudinal midportion of the portion 26 of the pintle and in the longitudinal midportion of the rotor 12, for additional symmetry and balance. Each cylinder 16 is in communication with the pintle ports 28 and 29 successively during each rotation of the rotor 12 so that the working fluid may be drawn in through the one port and expelled from a cylinder at the other port. Each cylinder bore receives, with a snug and efficient hydraulic fit, a piston 33, the outer end of which is spherical, as indicated at 36. The piston 33 has an annular groove 35 near its outer end which defines a neck portion 34 between the end or head 36 and the main body of the piston. The annular groove 35 is adapted to receive a connecting spring 37 which is split to permit contraction and to accommodate the spring when contracted. Outwardly from the end of the piston is a thrust plate 38 having a radial recess 38' for receiving the outer end portion of the piston to a point inwardly beyond the groove 35. The side walls of this recess are provided with an annular groove 38'' positioned to lie in the plane of the neck portion 34 or groove 35 when the end of the cylinder head rests against the bottom of the recess. This recess or counterbore 38' in the thrust plate 38 has a somewhat larger diameter than the outside diameter of the piston head so that at no time will it be possible for the side walls of the recess to engage the piston and transmit to or receive from the piston any twist or turning moment or reactionary force. Since the piston head is spherical, and is the only point of contact, only radial thrusts can be delivered at any time by the thrust plate to the piston on the pressure stroke so long as the thrust plate is both close to and normal to the axis of the piston. The piston is secured for limited floating movement relative to the thrust plate by compressing the spring 37 into the groove 35 of the piston then inserting the two into the thrust plate recess 38' and permitting the spring to assume its normal expansion and thus bridge between the groove in the thrust plate and the groove 35. The spring therefore loosely connects the piston and thrust plate for operating the piston on the suction stroke.

Each thrust plate 38 has a tangential plane outer face which abuts the complementary inner face of a segmental bearing plate 42 carried by the secondary rotor 43, so that the thrust plate and bearing plate may shift relatively to and from the direction of travel of the rotors to compensate for eccentricity. Guideways 39'' are provided in the coupling plates 39 for snugly engaging the opposite edges of the thrust plates so that the thrust plates may always be substantially normal to the axes of their cooperating pistons. It will be noticed that the member 38 has been termed "thrust plate" instead of "crosshead" as obviously the plate is not a driving crosshead for the piston in the same manner as the usual crossheads. It can exert no

other than radially acting forces on the piston and its share of the driving torque of the pump is limited only to the inertia its own body adds to the rotor mass. In fact, the piston head 36 shifts the thrust plate itself back and forth the very slight amount necessary along the complementary bearing plate 42, by means of the radial thrust due to the hydrostatic load on the piston. Thus no lateral contact between the two is needed during the pressure cycle to shift it through the medium of the piston head 36. During the suction cycle the centrifugal force is sufficient to slidably shift the thrust plate along the bearing 42, only a slight lateral reactance between the piston head 36 and the walls of the thrust plate recess 38' being necessary to resist this centrifugal force. It is noted that the centrifugal force acts to urge the thrust plate 38 in the proper direction during the pressure stroke. In this manner substantially all force required to compensate for eccentricity of the rotor during part of the rotation is provided without even the necessity of contact between the circumferential wall of the piston head 36 and the circumferential wall of the recess 38' in the thrust plate. 20

For ease in installation and also to permit the bearing plates 42 to move radially inwardly while remaining in fixed circumferential position within the secondary rotor 43, cylindrical radial studs 41 are provided, each plate being held firmly against the secondary rotor 43 by positive hydrostatic force as well as centrifugal force of its own. The studs, therefore, may slidably engage the bearing plates 42. The secondary rotor member 43 forms the inner ring of its supporting anti-friction bearings 44 which cooperate with a stationary housing or reactance ring 45. For ease in installation, the bearings 44 may be held in place by axially separate cage members 44' which are held together by means such as the screws 40 or other elements indicated at 44''. The reactance ring 45 is provided with a suitable means, such as indicated at 45', to receive the usual stroke control actuating means, indicated at 46, for shifting the axis of the ring 45. The ring 45 is maintained parallel to the axis of the barrel 12 by the usual abutments within the casing, not shown, and guided thereby during such movement. Within the casing 1 are abutments 47 for limiting the movement of the ring 45 for extreme adjustment of stroke. If in larger units the friction between the abutment surfaces and ring 45 make shifting of the ring difficult, anti-friction bearings may be provided therebetween. 50 55

It is apparent that the relation of each thrust plate 38 and its associated piston 33 is semi-floating, the radial load transmission and the centrifugal force of the piston during the pressure cycle being always sufficient to shift the sliding thrust plate in its real or true path along the bearing plate 42 and guideway 39". Thus by virtue of the novel coupling connection between the rotors, the novel mounting of the pistons in the thrust plates, and of the primary rotor in the casing, torque can be applied to one end of the rotor 12 and transmitted to the secondary rotor without torsional stress and in turn transmitted to the piston as a thrust having none but a radial component. 70

Due to the symmetrical arrangement of the parts of the coupling and the bearings 10 at the opposite sides of the pistons and equidistant from the piston axes, overbalance stresses, due to driving the rotor from one end and due to hy- 75

draulic reactances, are substantially eliminated. It will be clear from the above description that the manner in which the pistons are mounted in the thrust plates would be effective in those types of pumps wherein the piston itself and its complementary assemblages forms the driving coupling, but when combined with the separate coupling mechanism the results obtained by the conjoint use of the couplings and piston far exceed those heretofore obtained. By this arrangement high efficiency and durability with moderate slip and low operating temperature are obtained, the mechanical load being properly directed by the rigid coupling directly on the rigid couplings and the driving torque directly transmitted from one rotor to the other so that all shocks and torsional oscillations of the secondary rotor or the piston actuating reactance assemblies are relieved and the pistons, due to the delivered radial thrusts, are substantially entirely relieved from wall friction and bending and tilting stresses, and all forces acting thereon are utilized fully in performing the primary functions of suction and delivery of suitable hydraulic pressure. By the combination of the independent mechanical couple between the rotors and the base of piston mountings in the reactance means, it is possible to provide a pump of the radial piston type in which the forces introduced are utilized throughout most efficiently and no part of such forces is directed so as to be not only wasted but transformed into wear of the working parts.

Having thus described my invention,

I claim:

1. In a pump or motor of the character described, a casing, an internal annular bearing race within the casing, anti-friction bearings in said race, a cooperating inner bearing race within the casing, a rotor within the casing coaxial with said races and having a radially extending body and a hub protruding from the body at one end into and coaxial with the inner race and spaced radially therefrom, a secondary rotor mounted within the casing, coupling means driv- ingly connecting the rotors and an annular hub on the coupling means extending between the inner race and the rotor hub and having its circumferential surfaces in tight fitting contact with said rotor hub and inner bearing race respec- tively and said coupling means having a radial portion contiguous to the hub portion and extending between the radially extending body and adjacent end of said inner race and having its opposite face in juxtaposition with the said body and inner race for constraining said radial portion to fixed position axially of the axis of rotation.

2. In a device of the character described, a rotor having a plurality of circumferentially spaced radial cylinders, pistons reciprocable therein, a reactance rotor eccentric with respect to the cylinder rotor, a chordal bearing surface on the reactance rotor, a thrust plate having a plane bearing surface complementary to said chordal face, said thrust plate having a recess at its inner face extending normal to the axis of said plane surface and coaxial with one of said pistons when the rotors are rotated to a position in which their radii of rotation through the said one of said pistons and said thrust plate are superimposed, an end portion of said piston protruding into said recess and being of smaller diameter than said recess, an annular groove in the portion of the piston received in the recess, a complementary groove in the side wall of the

recess, a contractable spring disposed in the piston groove and contractable therein to permit insertion of the piston and spring together into said recess, whereby the spring may expand and bridge between said grooves for floatingly connecting the piston and thrust plate with the piston side walls spaced from the side walls of the thrust plate recess, and said recess having an abutment in the end wall thereof engageable with the end of the piston when the piston is connected to the thrust plate.

3. In a pump or motor of the character described comprising primary and secondary rotors, one rotor having a cylinder, valve means therefor, a piston carried by said cylinder and reciprocable radially thereof, a thrust plate interposed between the rotors, means mounting and guiding said thrust plate for movement radially only with respect to the rotor carrying the piston, a radial recess in the thrust plate of greater diameter than the piston for receiving the piston radially therein, said recess having an abutment wall engageable with the end of the piston when the piston is received therein, the end of the piston received therein having shoulders faced inwardly toward the piston rotor axis, and an expansible and contractable means interposed in the recess and cooperable with said piston shoulder for connecting the piston to the thrust plate with the piston side walls in spaced relation to the side wall of the recess and additional means operatively connecting the rotors for torque transmission independently of the pistons.

4. In a pump or motor, a casing, a primary rotor and a secondary rotor, means rotatably supporting said rotors in said casing, said rotors having substantially parallel axes of rotation, means mounting one of said rotors for movement into different adjusted positions wherein its axis is parallel to and offset from the axis of rotation of the other rotor, means to adjust said one rotor for changing the relative position of said parallel axes, a radial series of radial pistons reciprocably mounted in said primary rotor and actuated radially by said secondary rotor, coupling means between said rotors at each side of the pistons, said coupling means including a driving hub mounted between the primary rotor and its associated support and having a radial flange disc, a driven disc carried by the said secondary rotor and extending parallel to said driving disc, and planetating means between said discs and connecting the discs to positively couple said driving and driven members for rotation together in all adjusted positions of said one rotor.

5. In a rotary, radial piston pump or motor, a primary rotor, a secondary rotor in eccentric relation thereto, one of said rotors having a plurality of radial cylinders, pistons in said cylinders respectively, means in valving cooperation with the cylinders, thrust means connected to the pistons respectively and operatively interposed between the other of said rotors and the pistons respectively for reciprocating the pistons, said thrust means being shiftable to and fro along the path of rotation for compensating for tangential components of eccentricity of said rotors, and coupling means disassociated from said thrust means for drivingly connecting the rotors for torque transmission, said coupling means comprising a rigid radial flange in fixed position on one rotor at one side of the pistons, a plurality of circumferentially spaced guideways therein, another radial flange in fixed position on the other rotor in substantially face to face rela-

- tion to the first flange, a plurality of circumferentially spaced complementary guideways in said other radial flange and each complementary guideway extending operatively at right angles 5 to and associated one of the first guideways and aligned therewith longitudinally of the rotors, rigid coupling elements carried by said flanges and said elements having portions accommodated in and slidably along said aligned complementary 10 guideways respectively concurrently and drivingly connecting the rotors.
6. In a rotary, radial piston pump or motor, a cylinder rotor having a plurality of radial cylinders, valve means for the cylinders, a reactance rotor in eccentric surrounding relation to the cylinder rotor and having a circumferential wall and radial flange walls defining an internal recess open toward the cylinder rotor, pistons in the cylinders respectively, valve means for the 15 cylinders, thrust means disposed in the recess and mounted for oscillation therein, and cooperating respectively with the pistons for actuating the same, a radial flange wall on the cylinder rotor having a face substantially juxtaposed to the outer radial face of one of said flange walls, a tangential guideway in one of said juxtaposed flange walls, a radial guideway in the other of said juxtaposed walls, said guideways being aligned longitudinally of the rotor with each 20 other, a coupling element carried by said juxtaposed walls and entirely disassociated from said thrust means and having a tangential portion accommodated in and slidable along the tangential guideway, and a portion accommodated 25 in and slidable along the radial guideway.
7. In a rotary, radial piston pump or motor, a pair of rotors in eccentric relation to each other, radial piston and cylinder assemblies carried by the rotors and operated thereby consequent upon concurrent rotation of the rotors, valve means 30 for the assemblies, one of said rotors being in surrounding relation to the other rotor, a chordal guide carried by one rotor in fixed position relative thereto and spaced from the axis of rotation thereof, a radial guide carried by the other one of said rotors and in fixed position relative thereto, and extending radially inwardly and outwardly beyond both radial limits of the chordal guide, and a coupling element having portions 35 engaged with and slidable along said guides respectively concurrently, and being operative independently of and disassociated from the piston and cylinder assemblies.
8. In a rotary, radial piston pump or motor, a cylinder rotor having a plurality of radial cylinders, a reactance rotor in surrounding relation thereto, pistons in said cylinders respectively, valve means for the cylinders, said reactance rotor having a circumferential reactance wall and radial flange walls at each end of the circumferential wall and defining therewith a circumferential recess open toward the cylinder rotor, shoulders on the radially inward margins of said radial walls for engaging the inner working surfaces of piston heads to operate the pistons on their suction strokes, heads connected to the pistons and disposed in said recesses with their inner faces supported on said shoulders, thrust means interposed between the heads and circumferential wall of said reactance rotor, chordal 45 grooves in said radial walls, radial flanges carried by the cylinder rotor and lying alongside said radial walls of the surrounding rotor in substantially face to face abutting relation thereto, 50 radial grooves in said flanges aligned longitudinally of the rotors with said chordal grooves respectively, coupling blocks carried by said flanges in said guideways and reciprocable radially thereof and having portions accommodated for sliding action in said chordal grooves. 55
9. In a rotary, radial piston pump or motor, a cylinder rotor having a plurality of radial cylinders, pistons in the cylinders respectively, valve means for the cylinders, reactance rotor means in eccentric surrounding relation to the cylinder rotor and comprising radial wall elements arranged at opposite sides of the plane of the pistons, said pistons having portions extending between said radial wall elements, guideways in said radial wall elements for cooperation with the pistons, thrust means operating in said guideways and connected with the pistons respectively for actuating the pistons consequent upon concurrent rotation of the cylinder rotor and reactance rotor means, a reactance stator in fixed position longitudinally of the cylinder rotor, means mounting the radial wall elements in the stator for rotation and axially floating movement, and radial flanges on the cylinder rotor at the outer faces of said radial wall elements and having faces juxtaposed to the outer radial faces of said radial wall elements respectively for constraining the said elements to fixed axial position with respect to the cylinder rotor. 60
10. In a rotary, radial piston pump or motor, a casing, a cylinder rotor in the casing and having a plurality of radial cylinders, a reactance rotor means in surrounding relation thereto, pistons in said cylinders respectively, valve means for the pistons, said reactance rotor means comprising radial wall elements at opposite sides of the plane of the pistons, said pistons having portions extending between the radial wall elements, guideways in said radial wall elements for cooperation with the pistons, thrust means operating in said guideways and connected with the pistons respectively for actuating the pistons consequent upon concurrent rotation of the cylinder rotor and reactance rotor means a reactance stator in fixed position longitudinally of the cylinder rotor, means mounting the radial wall elements in the stator for rotation and axially floating movement, radial flanges carried by the cylinder rotor at the outer faces of said radial wall elements and having faces juxtaposed to the outer radial faces of said radial wall elements respectively for constraining the said elements to fixed axial position with respect to the cylinder rotor, anti-friction elements at each end of the cylinder rotor and mounting the cylinder rotor in the casing in fixed axial position, said cylinder rotor having end wall portions, and said anti-friction elements including inner race members abutting the radial flanges and holding the radial flanges in fixed axial position and abutting relation to said end wall portions of the cylinder rotor. 65
11. In a rotary radial piston pump or motor, a primary rotor, a secondary rotor in eccentric relation thereto, radial cylinders carried by one rotor, pistons carried in the cylinders respectively, thrust means on each piston operatively connecting the pistons to the other rotor for actuation of the pistons consequent upon concurrent rotation of the rotors, valve means for the cylinders, and positive coupling means between the rotors and disassociated from the pistons and thrust means, said coupling means comprising a plurality of guides on one rotor uniformly distributed circumferentially thereof, complementary guides carried in the other rotor and respective to the 70
- 75

first guides and extending at right angles each to an associated one of the first guides respectively in the plane parallel to the plane of the first guides, independent coupling elements cooperating one continuously with each pair of associated guides for drivingly connecting the rotors while compensating for tangential and radial components of eccentricity, each element being entirely disconnected from and operable independently of the remaining coupling elements, whereby torque transmission between the rotors is substantially uniform during the operation thereof.

12. In a rotary radial piston pump or motor, a primary rotor, a secondary rotor means for supporting the secondary rotor for adjustment into different positions wherein its axis is parallel to and offset from or co-incident with the axis of the primary rotor, means for adjusting the secondary rotor, radial cylinders carried by one rotor, pistons 20 carried in the cylinders respectively, thrust means

on each piston operatively connecting the pistons to the other rotor for actuation of the pistons consequent upon concurrent rotation of the rotors, valve means for the cylinders and positive planetating coupling means between the rotors and disassociated from the pistons and thrust means, said coupling means comprising independent coupling elements uniformly distributed circumferentially of the rotors and each coupling element being continuously connected to both rotors for planetating movement with respect to the combined rotors for drivingly connecting the rotors while compensating for tangential and radial components of eccentricity, each element being entirely disassociated from the remaining coupling elements and continuously operable in all relatively adjusted positions of said rotors, whereby torque transmission between the rotors is substantially uniform during the operation thereof.
